UNITED STATES PATENT OFFICE

DAVID B. MACKENZIE, OF MUSCATINE, IOWA

AUTOMATIC SASH MACHINE

Application filed March 12, 1928. Serial No. 261,035.

My invention relates to improvements in automatic sash machines, and it consists in the combinations, constructions, and arrangements herein described and claimed.

An object of my invention is to provide an automatic sash machine of the type relating to the manufacture of window stiles in which novel means is provided for feeding the stiles to the machine, boring, grooving, molding the stock on two edges, and dressing to proper thickness in a series of operations during which the stock, that is to say, the stiles pass through the machine into direct lines.

15 A further object is to provide an automatic sash machine in which novel means is provided for regulating the speed or the movement of the stiles from their grooving and boring positions to the sticking unit while 20 the machine is in operation, thereby providing a device which may be accurately and efficiently adjusted under actual working conditions.

25 A further object is to provide a device in which novel means is provided for actuating the feeding, boring, grooving, molding and dressing devices from a common source of power, and in which means is provided for synchronizing these various operations.

30 A further object is to provide a device having a pair of stile-manufacturing units for preparing rights and lefts at the same time, the operation of one unit alternating with respect to the other unit, thereby providing 35 a device having a double capacity and requiring only half the power.

35 A further object is to provide a device which while primarily designed for manufacturing stiles may also be quickly and 40 easily changed to run sash rails and other similar sash parts.

45 A further object is to provide a device in which the stiles may be finished as to thickness, thereby providing finished stiles which will result in a sash having uniform thickness when assembled from the stiles.

50 Other objects and advantages will appear in the following specification, and the novel features of the invention will be particularly pointed out in the appended claims.

My invention is illustrated in the accompanying drawings, forming part of this application, in which

Figure 1 is a side elevation of my device, 55
Figure 2 is a sectional view through a portion of my device,

Figure 3 is a top plan view of my device, 60
Figure 3A is an enlarged view showing a portion of my invention,

Figure 4 is a transverse sectional view of 65 the device shown in Figure 1,

Figure 5 is an enlarged detail view of a portion of my device,

Figure 6 is an enlarged detail view of the 70 hopper and feeding mechanism,

Figure 7 is a detail view taken substantially along the line 7—7 of Figure 6,

Figure 8 is a transverse sectional view of 75 the sliding bar associated with the feeding mechanism,

Figure 9 is a plan view of a portion of the device shown in Figure 8,

Figure 10 is a perspective view of a window sash,

Figure 11 is a detail view of a portion of 80 my device,

Figure 12 is a sectional detail view of a portion of my device, and

Figure 13 is a sectional view taken along 85 the line 13—13 of Figure 5.

In carrying out my invention, I make use of a pair of frame members 1 extending substantially the entire length of the machine. The base of the machine comprises a pair of channel members 2, see Figures 1 and 4, to 90 which the frame members 1 are firmly secured by suitable bolts 3. Suitable supporting means 4 are provided for firmly securing the side frame members 1 in spaced relation. One end of the frame members 1 is supported by a frame structure 5 forming a part of the sticking unit, as will be hereinafter described.

A shaft 6 is mounted upon the forward or hopper end of the frame members 1. The shaft 6 is disposed transversely of the frame members 1 and is supported by means of bearings 7. A pulley 165 is mounted upon one end of the shaft and bevel gears 9 and 10 are disposed upon the shaft, as shown in Figure 4. A pair of pulleys 11 is mounted 100

upon the shaft 6. Rotary motion is transmitted to shafts 12 upon which cutters 13 are mounted. Belts 14 passing around the pulleys 11 and pulleys 15 operatively connect the shaft 6 with the two shafts 12. The cutters 13, as will be seen from Figures 1 and 4, are disposed on the outer sides of the frame members 1 and relatively near the upper edge thereof. Referring to Figure 2, it will be seen that I have provided a shaft 16 which is supported between the frame members 1. Yokes 17 are pivotally mounted upon the shaft 16. The yokes 17 are provided with bearings 18 for supporting the shafts 12 upon which the cutters 13 are mounted.

A gear 19 is mounted upon a disc shaft 20, the latter being supported within bearings 21 carried by suitable brackets 22. These brackets are secured to the supporting means 4 by the provision of bolts 23. A disc cam 24 is mounted upon each end of the disc shaft 20, see Figure 3. The gear 19 is in mesh with a pinion 25 mounted upon a shaft 26. The latter is mounted within bearings 27, as shown in Figure 4. A chain 28 passing around a sprocket 29 upon the shaft 20 and around a sprocket 30 mounted upon a shaft 31 transmits power from the disc shaft 20 to the shaft 31. A pair of cams 32 is mounted upon the shaft 31. The cams 32, as will be seen from Figures 2 and 4, are arranged to engage a roller 33 mounted upon the yokes 17. The cams 32 are positioned 180° apart upon the shaft 31. The disc cams 24 are also positioned 180° apart upon the shaft 20. The purpose of positioning the cams 32 and the disc cams 24 180° apart will be more fully explained later.

Referring now to Figures 1 and 4, it will be noted that I have provided a drilling or boring mechanism A. There are two of these boring mechanisms, a unit disposed upon each side of the machine. Each of the boring mechanisms A is provided with a pair of boring bits 34. The bits 34 are disposed angularly with respect to the longitudinal axis of the machine in the manner shown in Figure 1. Since the two units are identical in construction and operation, the description of one unit will of course apply to the other. The bits 34 are inserted in spindles 35, see Figure 1, and are secured in place by means of tapered nuts 36. The spindles 35 are arranged for longitudinal movement within bearings 37, a connecting sleeve 38 and rotating sleeves 39 and 40. Rotary motion of the spindles is imparted by means of the bevel gear 9 mounted upon the shaft 6, as shown in Figure 4. Figure 4 shows a pair of bevel gears 9 and 10, the purpose of which is to operate the boring mechanism upon both sides of the machine. For the purpose of describing the construction of the device, the description will be limited to one unit.

The bevel gear 9 is in mesh with a gear

41 which is secured to the lower end of the sleeve 40. Gears 42 and 43 which are disposed in operative relation and integral with the sleeves 40 and 39, respectively, are adapted to transmit rotary motion to the boring bits 34 when the gear 41 is rotated. The spindles 35 are splined in the sleeves 39 and 40 so that the spindles 35 may be moved longitudinally with respect to the longitudinal axes of the latter. Means for raising and lowering the bits 34 consists in the provision of a lug 44, see Figure 4, which is attached to the connecting sleeve 38. The connecting sleeve is mounted between collars 45 which are attached to the spindles 35. The lug 44 extends inwardly through the side frame member 1. A lever 46 is pivotally mounted at 47 and arranged so that one end projects underneath the lug 44. A roller 48 is carried by the opposite end of the lever 46 and is arranged to be actuated by a cam surface 49 mounted upon the disc 24. A lever 46 is provided for each of the boring mechanisms A. The cam portions 49 associated with the disc cams 24 are disposed 180° apart so that during the rotation of the disc cams 24, the levers 46 will be actuated alternately, that is to say, when the boring bits 34 in one of the boring units are moved upwardly, the bits in the other unit are moved downwardly. An arrow 50 shown in Figures 1 and 2 indicates the direction of rotation of the shaft 20 and the disc cams 24. It will thus be seen that during the rotation of the disc cams 24, the cam surface 49 is designed so that the upward movement of the boring bits is gradual and relatively slow and the return movement of the bits will be relatively fast.

A table 51 is provided for each side of the machine. These tables are disposed upon the upper edge of the frame members 1, projecting outwardly and extending substantially the entire length of the machine. A guide member 52 is mounted upon each of the tables 51, see Figures 4 and 7. Suitable slots 53 are provided in the tables 51 for permitting the cutters 13 to pass above the upper face of the tables, see Figure 4. Referring to Figure 3, it will be noted that the tables 51 are provided with openings 54 which are in alignment with the boring bits 34 so that the latter may pass upwardly through the openings 54 and into window stiles, as will be hereinafter explained.

A hopper is provided consisting of stationary upright channel-shaped members 55 and similar members 56 movably mounted for adjustment toward and away from the members 55. The adjustable members 56 are secured to plates 57, as shown in Figure 2. The plates 57 are slidably disposed between parallel guide members 58 and 59, see Figures 2 and 4. Referring to Figure 3, it will be seen that the channel formation of the members 55 and 56 provides suitable guiding means

for window stiles, indicated generally at S in Figures 4 and 6. An inclined bridge 60 is provided, as shown in Figure 4 so that the stiles S when thrown upon the bridge 60 are permitted to work to both sides so that eventually the stiles will be deposited one at a time upon the tables 51. At this time it will be noted from Figure 6 that the stiles are deposited upon the tables 51 substantially above the boring bits. This end of the machine, that is, the end characterized by the channel members 55 and 56 will for the sake of convenience be called the front or forward end of the device. The stiles S are bored and grooved as they are dropped down upon the tables 51 and passed rearwardly over the cutters 13 to the sticking unit which forms the rear end of the machine.

The operation of each side of the machine is identical so that it is necessary to describe the actual operation and means for boring and grooving the stiles on one side of the machine. As will be seen from Figures 4 and 6, the stiles are in close contact and are fed by gravity downwardly in the direction of the tables 51. Since the movement of the bits 34 is upwardly, it is necessary to provide means for rigidly clamping the bottom stile securely so that it may be properly bored. Referring to Figure 4, it will be seen that I have provided guide plates 61 which are arranged so that the stiles S may be moved underneath the guide plate associated with each of the guide members 52. An arm 62 is pivotally mounted at 63 upon a bracket 64. A clamp plate 65 is adjustably secured to the upper end of the arm 62. A roller 66 is mounted upon the opposite end of the arm. A cam 67 mounted at 68 for movement with the spindles 35 is adapted to move the arm 62 into the dotted line position shown in Figure 4, at which time the clamp plate 65 is moved inwardly against the stile S for rigidly supporting the stile against the guide 52 and underneath the guide plate 61 while the stile is being bored.

Means for moving the stile along the table 51 after the boring has been completed consists in the provision of a sliding slotted bar 69. As will be seen from Figure 2, the bar 69 is connected at 70 with an arm 71 which in turn is connected at 72 with a lever 73, the latter being pivoted at 74 with the frame member 1. A connecting rod 75 is connected at 76 with the lever 73 and at 77 with the disc cam 24. The description at the present time relates to one unit, that is to say, one side of the machine and the description hereafter will also be limited to one side of the machine in so far as it is possible, since the two units are substantially identical. The sliding bar 69 is slidably supported by means of suitable brackets 78. In Figure 8, I have shown a detail of the brackets 78. It will also be noted in the same figure that a dog 79 is

secured to the sliding bar 69. The bar 69 is slotted at 80 and the dog 79 is arranged to project through the slot 80 and also a slot 81 in the guide member 52. Figure 6 shows the dog 79 engaging one of the stiles which is being moved along the table 51. The sliding bar 69 is grooved at 82 to receive the base portion 83 of the dog 79. A bolt 84 passing through the slot 81 and having a shoulder 85 is adapted to adjustably secure the dog 79 with respect to the sliding bar 69. Merely loosening the bolt 84 a small amount will permit the movement of the dog 79 for adjusting the dog as when changing the machine for different lengths of material.

Means for regulating the proper time for dropping a stile upon the table 51 after the preceding stile has been removed consists in the provision of a spring-pressed trigger 86 which is pivotally mounted at 87, see Figure 3. Normally, that is to say, while the stile is being bored, the trigger 86 is in the full line position so that the inward end 88 is positioned underneath the lower end of the channel-shaped members 55. It will be seen from Figure 3 that when the trigger 86 is in the full line position, the stile which is disposed upon the table 51 bears against the trigger and rearward movement of the stile in the direction of the sticking unit must necessarily move the trigger 86 about its pivot 87. This position is also shown in dotted lines in Figure 3. One end of a bar 89 is pivotally connected at 90 with the trigger 86. The opposite end of the bar is adjustably connected with a pivoted arm 91, the latter being mounted upon the plate 57. The arm 91 is provided with a lug 92 which is disposed relatively near the lower end of the channel-shaped members 56, see Figures 1 and 3.

Referring to Figure 11, it will be noted that the bar 89 is serrated at 93 on one edge thereof. The arm 91 is looped at 94, see Figure 12, and the loop portion 94 is provided with a suitable lug 95. The lug is adapted to engage the serrated portion of the bar 89. A clamping lever 96 is pivotally mounted at 97 upon the arm 91. As will be seen from Figures 11 and 12, the clamping arm 96 is adapted to rigidly secure the bar 89 with respect to the arm 91. It will now be seen that when the trigger 86 (referring to Figure 3) is moved from the full line position into the dotted line position, a relative movement of the bar 89 has taken place. The movement of the bar 89 is in the direction of the arrow 98. Such movement of the bar 89 will cause a relative movement of the arm 91, resulting in a movement of the lug 92 into a position whereby the latter is adapted to support the stiles which would otherwise fall upon the table 51.

When moving the channel-shaped members 56 toward or away from the channel

shaped members 55, as when adjusting the hopper for stiles of different lengths, the trigger mechanism, that is to say, the means for preventing the stiles from falling upon the table 51, except at predetermined intervals, may be easily adjusted as when the channel-shaped members 56 are moved, by merely lifting the clamping lever 96 to free the bar 89 with respect to the arm 91. When the channel-shaped members 56 have been adjusted to their proper position, the clamping lever 96 is again moved into its locking position for securing the bar 89 with respect to the arm 91. A spring 99 is arranged for normally holding the trigger 86 in the full line position shown in Figure 3. The inward end 88 of the trigger 86 is shaped so that movement of a stile against the trigger will cause the trigger to be moved freely for permitting passage of the stile along the table 51. Immediately upon a stile moving completely out of the hopper, that is, free from the channel-shaped members 55, the spring 99 will immediately move the trigger back into the full line position, at which time the lug 92 is moved out from underneath the end of the channel-shaped members 56.

Means for properly holding the stiles to the table 51 during the grooving process (see Figure 1) consists of a bar 100 pivotally mounted at 101 and provided with a roller 102. The roller 102 bears against one edge of the stile while the latter is passing from the hopper and over the cutter 13. A weight 103 is provided for adjusting the amount of pressure upon the stile. Suitable guide members 104 are disposed along the table 51 for guiding the stiles in their movements rearwardly along the table. During the movement of the stile, the latter is held against the face of the guide member 52.

When the stiles S are moved rearwardly by the action of the dog 79 a predetermined distance, as shown in Figure 6, the stiles are passed underneath the first of a series of feed rollers 105. Referring to Figure 3, it will be noted that the feed rollers are mounted upon each end of a series of shafts 106 in such a manner that the rollers are properly aligned for moving the stiles rearwardly in a straight line to the sticking unit, as will be more fully explained later. It will be noted from Figure 1 that the shafts 106 are mounted within bearings 107 carried by arms 108. The arms 108 are pivotally mounted upon shafts 109, see Figure 3. The provision of the arms 108 permits the feed rollers 105 to be independently adjusted toward or away from the tables 51. This adjustment is made by turning hand screws 110, see Figure 1. This adjustment permits the feed rollers to be changed to accommodate stock of varying widths. Suitable brackets 111 are provided for supporting the shafts 109. A pair of relatively large feed rollers 112 is mounted

upon each side of the machine and in alignment with the feed rollers 105. These rollers are also mounted upon suitable arms 113 which are adjustable by means of the hand screws 110. The arms 113 are pivotally mounted upon a shaft 114 and the feed rollers 112 are mounted upon shafts 115. Rollers 116 are disposed between the rollers 112, see Figure 1, and relatively near side cutters 117. The rollers 116 may be adjusted by means of a hand screw 118. The side cutters 117 are mounted upon a shaft 119.

Top cutter heads 120 are mounted upon a shaft 121. The shaft 121 is mounted upon the frame 5 of the sticking unit. Bottom cutter heads 122 are mounted upon the frame 5 and underneath the top cutter heads 120. The top cutter heads 120 and the bottom cutter heads 122 are disposed in a vertical plane through the line of travel of the stock along the tables 51.

The stiles are passed from the feed rollers 112 between power driven rollers 123 and 124, see Figure 3. The rollers 124 are disposed so that the periphery of the rollers is in line with the guide members 52. An idler 125 is disposed upon each side of the machine, as shown in Figure 1. The rollers 123 are mounted upon yokes 126. Referring to Figure 3, springs 127 may be actuated by means of a hand wheel 128 for adjusting the rollers 123 to or away from the stiles passing between the rollers as required by reason of the different thicknesses of the various forms of stiles. The rollers 123 are mounted upon vertically-disposed shafts 129 and the rollers 124 are mounted upon vertically-disposed shafts 130. A plurality of shafts 131, 132, 133 and 134 is carried by the frame 5 of the sticking unit, see Figures 5 and 2. Bevel gears 135 and 136 are mounted for longitudinal adjustment upon the shafts 131 to 134 inclusive. The shafts 129 and 130 are provided with bevel gears 137, see Figure 2, which are in engagement with the gears 135 and 136. Referring to Figure 5, it will be seen that the bevel gears 135 rotate the rollers 123, and the bevel gears 136 rotate the rollers 124.

As will be seen from Figure 5, the shafts 131 to 134 inclusive are disposed transversely of the frame 5 of the sticking unit and are provided with gears 138, 139, 140 and 141 mounted upon one end of the shafts. A shaft 142 is mounted upon the frame 5, as shown in Figures 5 and 1. A gear 143 is mounted upon the shaft 142 and is disposed in engagement with the gears 138 and 139, see Figure 13. An idler gear 144 is disposed in operative engagement with the gears 139 and 140, and an idler gear 145 is disposed in engagement with the gears 140 and 141, as shown in Figure 13. Thus it will be seen that rotation of the shaft 142 will cause relative rotation of the shafts 131 to 134 inclusive.

A relatively large gear 146 is mounted upon the oposite end of the shaft 142, see Figure 1. The gear 146 is in mesh with a gear 147 which is mounted upon a shaft 148. A gear 149 mounted upon the shaft 148 is in mesh with a gear 150 mounted upon a shaft 151. A pulley 152, see Figures 1 and 3, is mounted upon the shaft 151. A belt 153 is passed around the pulley 152 and a drive pulley 154 mounted upon a main drive shaft 155. The main drive shaft 155 is mounted within bearings 156 supported by brackets 157 which are secured to the frame 5 of the sticking unit.

A drive pulley 158 is mounted upon the shaft 155. A belt 159 is passed around the pulley 158 and a pulley 160, see Figure 1. The pulley 160 is mounted upon a shaft 161 carried by bearings 162, as shown in Figure 5. The shaft 6 is operatively connected with the shaft 161 by means of a belt 163 which passes around a pulley 164 mounted upon the shaft 161 and the pulley 165 mounted upon the shaft 6. In referring to Figures 2 and 5, it will be noted that a gear 166 is mounted upon one end of the shaft 161. This gear is in mesh with a gear 167 mounted upon a shaft 168 which is supported by suitable bearings 169. A cone pulley 170 is mounted upon the shaft 168. A second cone pulley 171 disposed in a reversed position with respect to the pulley 170 is operatively connected with the latter by means of a belt 172. Belt-shifting means 173 operatively connected with a threaded shaft 174 is disposed between the cone pulleys, as shown in Figure 5. The shaft 174 is angularly disposed with respect to the longitudinal axis of the machine so that the belt-shifting means 173 may be moved for shifting the belt 172 longitudinally of the cone pulleys 170 and 171 in such a manner that the belt-shifting means moves parallel with the cone pulleys between which it is disposed.

A sprocket 175 is mounted for rotation with the cone pulley 171. A chain 176 passes around the sprocket 175 and around a sprocket 177 associated with a clutch mechanism C mounted upon the shaft 26. Levers 178 disposed upon each side of the machine and connected by means of a link 179 permit the clutch mechanism C to be actuated from either side of the machine.

Referring to Figure 5, I have provided a shaft 180 mounted within bearings 181. A gear 182 mounted upon the shaft 180 is in mesh with a gear 183 mounted upon the shaft 151. A sprocket 184 is mounted upon the shaft 180. A chain 185 passes around this sprocket and sprockets 186 mounted upon the shafts 115. Rotation of the feed rollers 112 is provided through the medium of the chain 185.

Means for actuating the feed rollers 105 consists in the provision of a chain 187 which

passes around sprockets 188 mounted upon the shafts 106, see Figure 2. The chain 187 passes around an idling sprocket 189 and a sprocket 190 mounted upon a shaft 191. Means for driving the chain 187 consists of a sprocket 192 mounted upon the shaft 180. The chain 185 passes around an idling sprocket 193. Sprockets 194 are mounted upon the shaft 191. The sprockets 194 are disposed in a common plane with the chain 187. A feed chain 195 passes around the sprockets 194 and similar sprockets 196 mounted upon a shaft 197. The sprockets 196 may be adjusted by means of a take-up 198. As will be seen from Figure 1, the sprockets 196 are mounted relatively near the hopper end of the machine. The travel of the feed chain 195 is timed so that its speed is equal to the peripheral speed of the feed rollers 105. Referring now to Figure 7, it will be seen that the table 51 is grooved at 199 to receive a channel member 200. The channel member 200 provides a suitable runway for the chain 195. The feed chain 195 is mounted so as to be substantially flush with the upper surface of the table 51.

Referring to Figure 2, it will be noted that the frame members 1 are adjustably connected with the frame 5 by means of bolts 201. An extended portion 202 of the frame members 1 passes through the frame 5 and terminates relatively near the bottom cutter heads 122. Slight adjustments may be made by means of the bolts 201 for adjusting the extended portion 202 with respect to the bottom cutter heads 122. Blocks 203 are mounted upon each side of the frame 5 and in longitudinal alignment with the extended portion 202. The blocks 203 are arranged for angular movement by means of a screw 204 so that the upper surface of the blocks may be properly adjusted with respect to the cutter heads 122. Proper adjustment of the upper cutter heads 120 may be made through the medium of a hand screw 205. Rotation of the upper and lower cutter heads is provided through the medium of a belt 206 passing around a pulley 207 mounted upon the main drive shaft 155. The belt 206 passes over a pulley 208 mounted upon the shaft 119 and a pulley 209 mounted upon the shaft 121. The side heads 117 which are mounted upon the shaft 119 are rotated through the medium of the belt 206.

In Figure 10, I have shown the manner in which the stiles are finished in passing through the machine. As will be seen, the stiles S are molded or finished upon both edges and are bored, as at B, for receiving the knot or other fastening devices common in the art. A groove G is also cut in the sashes for receiving the sash cord.

From the foregoing description of the various parts of the device, the operation thereof may be readily understood. The main

shaft 155 may be rotated by means of any suitable source of power. Rotation of the main shaft will cause a movement of the belt 159 which passes around the pulleys 158 and 160, thereby actuating the cone pulleys 170 and 171. Rotation of the cone pulley 171 results through the belt 172 which passes around the cone 170. The sprocket 175 associated with the cone 171 transmits movement to the chain 176 which passes around the sprocket 177. The levers 178 may be moved for actuating the clutch mechanism C whereby rotation is given to the shaft 26. Rotation of the shaft 26 will of course cause a relative rotation of the disc shaft 20.

The rotation of the latter causes the disc cams 24 to rotate. As shown in Figure 1, the rotation of the disc cam 24 is in the direction of the arrow 50. During the rotation of the cam, the roller 48 will be moved by the cam surface 49 for raising the boring bits 34. Immediately before the boring bits 34 have reached the stile which is disposed upon the table 51, the arm 62 will be moved so as to bring the clamp plate 65 into engagement with the stile, see Figure 4, whereby the stile will be rigidly supported against the guide member 52. The guide plate 61 also tends to support the stile in that the plate prevents the stile from moving upwardly and away from the table 51 when the bits 34 pass into the stile. The arm 62 is caused to pivot when the cam 67 which is carried by the boring mechanism is moved into the dotted line position shown in Figure 4. Movement of the bits 34 into the stile results in the bores B shown in Figure 10. The distance the bits 34 are moved is determined by the cam surface 49.

Let us now refer to Figure 2 in which I have shown the lever 73 as being operatively connected with the disc cam 24 by means of the link 75. Rotation of the disc cam 24 will cause a reciprocating movement of the sliding slotted bar 69 which is connected with the lever 73 by means of the arm 71. During the operation of the machine and during the time that the stile which is being bored is disposed upon the table 51, the dog 79 which is connected with the bar 69 is positioned in its extreme forward position X, see Figure 6. While of course the rotation of the disc cam 24 is constant and the sliding bar 69 moves in a reciprocating path continually during the rotation of the disc cam, it will be seen that the dog 79 moves a sufficient distance forward of the channel-shaped member 56 to permit sufficient time for the boring bits 34 to pass into the stile and to be withdrawn before the dog 79 engages the end of the stile for moving it so as to bring one end of the stile between the first of the series of rollers 105 and the feed chain 195.

Movement of the stile in the direction of the sticking unit is understood to be rear-

wardly. The dog 79 which may be adjusted with respect to the sliding bar 69 moves rearwardly with respect to the channel-shaped member 56 a distance indicated between the arrows W. This distance is equal to the distance indicated between the arrows W'. The dog 79 should always be adjusted so that its movement will terminate, as shown in the full line position in Figure 6. When passing stiles through the machine which are either shorter or longer in length, the channel-shaped members 56 are properly adjusted and the dog 79 is then adjusted so that the distance W will always be the same.

When adjusting the machine for various lengths of stiles, the sliding bar is moved into its extreme rear position and the dog 79 is then moved to a position from the channel-shaped member 56 a distance equal to the arrows W. Movement of the sliding bar for adjusting the dog 79 may be performed by turning a hand wheel H which is mounted upon the shaft 26, whereby the disc cam 24 is rotated for moving the connecting rod, which is operatively connected with the sliding bar, into its extreme rearward position.

As soon as the boring bits 34 have been withdrawn from the stile which is being passed through the machine, the stile is moved rearwardly by means of the dog 79 and during the passage, the cutter 13 is moved upwardly through the slot in the table 51 so that the groove G shown in Figure 10 is effected. It will be seen that the cutter 13, see Figure 2, which is actuated by the cam 32, is operatively connected with the shaft 20 upon which the disc cam 24 is mounted. It will now be seen that the cutter 13, the sliding bar 69 and the boring bits 34 are operatively connected with the disc cam 24 so that the movement of each of these features may be properly synchronized.

Referring to Figure 3, it will be noted that as soon as the stile is moved rearwardly, the trigger 86 will be moved, thereby moving the bar 89 in the direction of the arrow 98. Such movement will cause a relative movement of the pivoted arm 91 upon which the lug 92 is secured. This movement brings the lug 92 into a position underneath the channel-shaped member 56 in such a manner that the stile is prevented from dropping upon the table 51 until the arm 91 has been moved back. This movement occurs as soon as the stile which is being grooved and bored has passed entirely from the hopper, whereupon the trigger 86 springs back into a position for moving the arm 91.

When once the stile has been passed from the hopper, it is taken by the feed rollers 105 and the feed chain 195 and moved rearwardly past the side cutter 117, through the power driven rollers 123 and 124, and between the bottom cutter 122 and the upper cutter 120. The stiles pass through the sticking unit in a

continuous unbroken line. It will therefore be seen that it is important that the stiles be fed to the sticking unit as rapidly as the latter can take care of the stiles.

5 The feed rollers 112 are adjusted so that their peripheral speed is the same as the speed of the power driven rollers 123 and 124. The stiles are stopped momentarily in the hopper during the boring process. In order to provide a continuous supply of stiles through the sticking unit, the speed of the feed chain 195 and the rollers 105 is accelerated with respect to the speed of the feed rollers 112 so that the stile which is being bored and grooved will 10 overtake the stile ahead which is being passed through the sticking unit. For this reason, it is necessary to provide means for accelerating the frequency with which the stiles are ejected from the hopper. This acceleration is attained through the cone pulleys 170 and 171. It will be seen from Figure 5 that the belt 172 may be moved longitudinally with respect to the cone pulleys, thereby increasing or decreasing the ultimate speed of the sprocket 15 175 which is operatively connected with the cone 171. The chain 176 which passes around the sprocket 175 operatively connected with the cone 171 and around the sprocket 177 mounted upon the shaft 26 permits the disc 20 cam 24 to be rotated at various speeds for increasing or decreasing the boring, grooving and movement of the stiles from the hopper. It will thus be seen that the rotation of the disc shaft 20 is determined by the speed ratio 25 of the cone pulleys 170 and 171.

Assuming that the rate of feed through the sticking unit is fifty feet per minute, it will be seen that twenty-five stiles, two feet in length, must necessarily pass through the 40 sticking unit in order to keep the machine working at full capacity. Should the stiles be four feet in length, the number of stiles delivered from the hopper must be reduced twelve and one-half per minute. As one stile 45 is bored, grooved and ejected from the hopper with each revolution of the disc shaft 20, it will be seen that the ejection of the stiles from the hopper may be accurately adjusted by the cone pulleys 170 and 171. An important feature of my device is that the belt passing 50 about the cone pulleys may be adjusted while the machine is running under normal working conditions. This permits the machine to be so adjusted that the stiles will be fed to the sticking unit as rapidly as the stiles pass through the unit, thereby permitting a maximum capacity of the machine at all times.

Another important feature of my machine 60 is that the boring and grooving mechanism may be readily disconnected by removing the belt 163 from the pulley 165, disengaging the lever 46 by removing the bolt 47, and removing the chain 28. When these changes have 65 been made, sash rails and similar parts which

require no grooving or boring may be run through the machine.

It will now be seen that I have provided a machine which is operated from one main drive shaft, and a machine which is substantially automatic in its operation in that the feeding, boring, grooving, and dressing both edges and one side of the window sash stiles is carried out automatically after a supply of stiles has been placed in the hopper. The machine consists of two units so that right and left stiles are produced in pairs, the units being so arranged that while one stile is being bored and grooved by one of the units, the boring bits and cutters of the other unit are out of engagement with the stile, thereby providing a machine in which the strain upon the various parts is reduced to a minimum, and a machine which while embodying two units requires merely sufficient power for propelling one unit at any given time. The upper and lower cutters and the side cutters are all driven from one belt, as shown in Figure 1.

I claim:

1. An automatic sash machine comprising a hopper, boring means disposed upon each side of the machine and arranged for boring a hole in the lowermost pieces of stock in the hopper, ejecting means disposed upon each side of the machine for moving the pieces of stock from the hopper, means for dressing the stock, means for conveying the stock from the hopper to said dressing means, a shaft, a pair of cams mounted upon said shaft, said cams being disposed in alternate relation, means connecting said cams with said boring means, means connecting said cams with said ejecting means, a main drive shaft, and means for operatively connecting said shaft with said main drive shaft. 90

2. An automatic sash machine comprising a hopper, boring means disposed upon each side of the machine and arranged for boring a hole in the lowermost pieces of stock in the hopper, ejecting means disposed upon each side of the machine for moving the pieces of stock from the hopper, means for dressing the stock, means for conveying the stock from the hopper to said dressing means, a shaft, a pair of cams mounted upon said shaft, said cams being disposed in alternate relation, means connecting said cams with said boring means, means connecting said cams with said ejecting means, a main drive shaft, variable speed means, means for operatively connecting said shaft with said variable speed means, and means for operatively connecting said main drive shaft with said variable speed means. 110

3. An automatic sash machine comprising a hopper, boring means disposed upon each side of the machine and arranged for boring a hole in the lowermost pieces of stock in the hopper, ejecting means disposed upon each side of the machine for moving the pieces of 125 stock from the hopper, means for dressing the stock, means for conveying the stock from the hopper to said dressing means, a shaft, a pair of cams mounted upon said shaft, said cams being disposed in alternate relation, means connecting said cams with said boring means, means connecting said cams with said ejecting means, a main drive shaft, variable speed means, means for operatively connecting said shaft with said variable speed means, and means for operatively connecting said main drive shaft with said variable speed means. 130

stock from the hopper, means for dressing the stock, means for conveying the stock from the hopper to said dressing means, a shaft, a pair of cams mounted upon said shaft, said cams being disposed in alternate relation, means connecting said cams with said boring means, means connecting said cams with said ejecting means, a main drive shaft, variable speed means, means for operatively connecting said shaft with said variable speed means, means for operatively connecting said main drive shaft with said variable speed means, and means for operatively connecting the main drive shaft with said dressing means.

4. An automatic sash machine comprising a hopper, boring means disposed upon each side of the machine and arranged for boring a hole in the lowermost pieces of stock in the hopper, ejecting means disposed upon each side of the machine for moving the pieces of stock from the hopper, means for dressing the stock, means for conveying the stock from the hopper to said dressing means, a shaft, a pair of cams mounted upon said shaft, said cams being disposed in alternate relation, means connecting said cams with said boring means, means connecting said cams with said ejecting means, a main drive shaft, variable speed means, means for operatively connecting said shaft with said variable speed means, means for operatively connecting said main drive shaft with said variable speed means, means for operatively connecting the main drive shaft with said dressing means, and means actuated by the movement of stock from the hopper for controlling the movement of stock in the hopper into operative relation with respect to said boring means.

5. An automatic sash machine comprising a hopper, movable boring means for boring a hole in the lowermost piece of stock in the hopper, a sticking unit, ejecting means for moving the piece of stock from the hopper in the direction of the sticking unit, a main drive shaft, means for connecting the drive shaft with said boring means for rotating the same, a cam, means operatively connecting the cam with said ejecting means, and means operatively connecting the cam with said boring means whereby the latter may be moved toward and away from the stock in said hopper.

6. An automatic sash machine comprising a frame, a hopper, movable boring means disposed upon opposite sides of the frame and arranged for boring holes in the lowermost pieces of stock in the hopper, a sticking unit, ejecting means associated with each side of the frame for moving the pieces of stock from the hopper in the direction of the sticking unit, a main drive shaft, means connecting the drive shaft with said boring means for rotating the same, a pair of cams, means op-

eratively connecting the cams with their respective ejecting means, and means operatively connecting the cams with the boring means upon their respective sides whereby the boring means may be moved toward and away from the stock in said hopper, the boring means and said ejecting means being alternately arranged and operated with respect to each other.

7. An automatic sash machine comprising a hopper, movable boring means for boring a hole in the lowermost piece of stock in the hopper, a sticking unit, ejecting means for moving a piece of stock from the hopper in the direction of the sticking unit, a main drive shaft, means for connecting the main drive shaft with said sticking unit, a cam, means operatively connecting the cam with said boring means whereby the same may be moved toward and away from the stock in the hopper, variable speed means operatively connected with said drive shaft, means for operatively connecting the cam with said variable speed means, grooving means for cutting a groove in the piece of stock moving from the hopper, and means for operatively connecting the grooving means with said main drive shaft.

Signed at Muscatine, in the county of Muscatine and State of Iowa, this 6th day of March, A. D. 1928.
